UNITED STATES PATENT OFFICE.

RANSOM W. DAVENPORT, OF DETROIT, MICHIGAN, ASSIGNOR TO DETROIT STOVE WORKS, OF DETROIT, MICHIGAN, A CORPORATION OF MICHIGAN.

COOK-STOVE.

1,212,458.

Specification of Letters Patent. Patented Jan. 16, 1917.

Application filed October 11, 1915. Serial No. 55,262.

To all whom it may concern:

Be it known that I, RANSOM W. DAVENPORT, a citizen of the United States of America, residing at Detroit, in the county 5 of Wayne and State of Michigan, have invented certain new and useful Improvements in Cook-Stoves, of which the following is a specification, reference being had therein to the accompanying drawings.

10 The invention relates to cook stoves, and is more particularly designed for the alternative use of solid and gaseous fuel.

The invention comprises the novel construction and arrangement of the gas burner 15 in a flueless portion of the stove wall; further the means for directing and distributing the heated gases therefrom; further the construction of automatic dampers for venting the oven when the gas burner is in use and 20 closing said vents when not in use; and further in various structural features as herein-after set forth.

In the drawings, Figure 1 is a sectional plan view of the stove; Fig. 2 is a vertical 25 cross section thereof; and Fig. 3 is a vertical longitudinal section. Fig. 4 is a fragmentary perspective view showing the rear portion of the stove.

A is a cook stove of usual construction 30 provided with a fire-box B, oven C and flues D E F and G, respectively extending across the top of the oven, down the end beneath the bottom and upward at the rear. It is usual in the construction of such stoves to 35 have the rear flue G of less width than the rear wall of the oven, and it is also usual to provide the rear wall of the oven with a rearward swell to increase the capacity of the oven. This swell or rearward extension 40 is beyond the vertical plane of the rear wall of the bottom flue, while it is inside the plane of the front wall of the rear flue.

It is the primary object of the present invention to so dispose the gas burner that it 45 will not interfere with the transference of heat from the flues to the oven and at the same time will be effective for heating the oven. This I have accomplished by placing the burner H in the swell or rearward extension I of the oven rear wall. In this way obstruction of heat from the bottom flue to the

oven is avoided. The burner H is introduced into this portion through an aperture J at one edge of the swell, and the jets of the burner are directed forward or toward the 55 oven front, the plane of the burner being but slightly above the plane of the oven bottom. One objection to such an arrangement is that the flame from the burner is directed toward the front so that upon opening the 60 oven door the heated gases would be deflected outward. This objection I overcome by placing a removable false bottom K above the oven bottom and burner H, and providing this removable false bottom with a downwardly-extending front flange L, which 65 closes the space therebeneath. I also preferably provide downwardly-extending deflector ribs M M', which are inclined to contract the path of the gases from the burner 70 as they bridge the front, and to permit the lateral deflection of said gases beyond the ends of said ribs to the oven sides. A series of apertures N or other cut-away portions of the deflector A will then permit the gaseous products to rise and pass through the 75 body portion of the oven.

To support combustion air must be admitted to the gas burner, and the products of combustion must be carried off. The admission of air may be provided by a series of apertures O along that portion of the swell I in the oven rear wall which is not covered by the rear flue G, and the exit of the products of combustion may be through a 80 port P from the top of the oven into said rear flue. When the gaseous fuel is not used, it is desirable to close the vents by dampers 85 Q and R, and as these are both adjacent to the rear wall of the oven they may be readily 90 connected by means such as S, so that the actuation of one will also effect that of the other. Thus the construction is one in which the presence of the gas burner does not interfere with the heating of the oven from gases 95 passing through the flues, and it is also one permitting a simple construction of vent controlling dampers and an effective arrangement for distributing the heated gases from the burner.

100 What I claim as my invention is:—

1. In a cook stove, the combination with an

oven provided with top, end, bottom and rear flues, of a rear wall for said oven having a swell or rearward extension beyond the bottom flue and in front of the rear flue, and a 5 gas burner located in said swell or rearward extension.

2. In a cook stove, the combination with an oven provided with top, end, bottom and rear flues, of a rear wall for said oven having a swell or rearward extension therein 10 beyond said bottom flue and in front of said rear flue, a burner extending horizontally in said swell or rearward extension above the plane of the oven bottom, and a removable 15 false bottom for said oven above said burner having means for intercepting the escape of gases to the front.

3. In a cook stove, the combination with an oven having a bottom flue and rear flue 20 connected therewith, covering only a portion of the rear wall of the oven, of a swell or rearward extension of the oven rear wall beyond said bottom flue, a gas burner located in said rearward extension arranged 25 horizontally above the oven bottom, an air inlet to the burner in the portion of said rear wall uncovered by said flue, and an outlet in the portion of said rear wall covered by said flue.

30 4. In a cook stove, the combination with an oven having a bottom flue and a rear flue connected therewith of less width than the rear wall of the oven, said rear wall having a swell or rearward extension beyond said 35 bottom flue, a gas burner extending horizontally in said swell adjacent to the bottom of the oven, and connected draft dampers controlling draft openings in said rear wall, the inlet opening being at the bottom of the un- 40 covered portion of said wall, and the outlet opening being in the covered portion opening into said flue.

5. In a cook stove, the combination with an oven, of a gas burner extending horizontally 45 along the rear wall of said oven above the bottom thereof and having inwardly-directed jets, and a horizontal false bottom above said burner having a downturned flange at the front for preventing the forward escape of the combustion gases.

6. In a cook stove, the combination with an oven, of a gas burner arranged along the rear wall thereof above the oven bottom and having forwardly-directed jet openings, a 55 removable false bottom covering said burner and provided with a downturned front flange for preventing escape of the combustion gases, and deflector partitions depending from said false bottom for directing the 60 combustion gases toward the center at the front and permitting escape at the opposite side.

7. In a cook stove, the combination with an oven, of a gas burner arranged along the 65 rear wall of said oven and having for-

wardly-directed jet openings, a false bottom above said burner having a downturned front flange for preventing the escape of the combustion gases, and oblique deflector flanges for directing the combustion gases 70 toward the center at the front and laterally to the opposite sides and having ports or openings at the sides for permitting the upward escape of said gases adjacent to the oven sides.

8. In a cook stove, the combination with an oven having a flue at the bottom thereof and a connecting flue at the rear of lesser width than the oven, a rear wall for said oven having a swell or rearward extension 80 therein, a gas burner extending horizontally in said rear extension entering through the portion of said swell uncovered by said rear flue, the jets from said burner being directed forward, a false bottom arranged above said 85 burner and having a downward flange at its forward end for preventing escape of the combustion gases, a deflector for directing the gases toward the opposite sides of said false bottom, dampers controlling draft 90 openings for said burner, the inlet being arranged in the portion of said swell uncovered by said rear flue and the outlet being in the covered portion and opening into said rear flue, connections between said dampers 95 for simultaneous operation thereof, and an actuating member extending outside of the oven.

9. In a cook stove, the combination with an oven, of a gas burner arranged along the 100 rear wall thereof above the oven bottom and having forwardly directed jet openings, a removable false bottom covering said burner and co-acting with the oven bottom to form a passage for the combustion gases from 105 said burner, and deflector partitions depending from said false bottom for directing the combustion gases toward the center of said passage and permitting escape of said gases at the front of said passage to the sides 110 thereof.

10. In a cook stove, the combination with an oven, of a gas burner arranged along the rear wall thereof above the oven bottom and having forwardly directed jet openings, a 115 removable false bottom covering said burner and provided with a down-turned front flange for preventing escape of the combustion gases and means located within the passage formed between said false bottom and 120 the oven bottom for deflecting the combustion gases from said burner toward the center of said passage and for permitting escape of the gases at the front of said passage to the sides thereof.

11. In a cook stove, the combination with an oven, of a removable false bottom spaced above the oven bottom and forming therewith a passage for combustion gases, a burner disposed below said false bottom ad- 130

5 jacent one of the oven walls, said burner having jet openings directed from said wall and deflector partitions depending from said false bottom for directing the combustion gases toward the center of said passage and allowing escape of the gases at their ends to the sides of said passage.

In testimony whereof I affix my signature in presence of two witnesses.

RANSOM W. DAVENPORT.
